UNITED STATES PATENT OFFICE.

SEWELL A. KNAPP, OF SAN FRANCISCO, CALIFORNIA.

COMPOSITE BARREL.

Application filed April 12, 1920. Serial No. 373,049.

To all whom it may concern:

Be it known that I, SEWELL A. KNAPP, a citizen of the United States, residing at city and county of San Francisco and State of California, have invented a new and useful Improvement in Composite Barrels, of which the following is a specification.

This invention relates to a barrel construction and particularly pertains to a composite knock down barrel.

It is the principal object of the present invention to provide a barrel which may be cheaply made while withstanding rough usage and which will satisfactorily preserve the contents of the barrel from the action of air and moisture, said barrel being so constructed as to be readily knocked down when empty.

The invention contemplates the use of special barrel heads comprising a ring rolled from sheet metal to form a croze adapted to receive a separable wooden head, said sheet metal ring being further designed so as to receive a chine ring which rests upon the wooden head, said head rings being readily assembled in connection with wooden barrel staves by which an air tight composite barrel is completed.

The invention is illustrated by way of example in the accompanying drawings, in which:

Figure 1 is a view in side elevation showing the present invention with parts broken away to more clearly disclose its construction.

Fig. 2 is a view in end elevation showing one of the barrel heads.

Fig. 3 is a fragmentary view in side elevation showing the adjustable fastening means for the barrel hoops.

Fig. 4 is a view in section through the structure shown in Fig. 3, as seen on the line 4-4.

Fig. 5 is an enlarged fragmentary view showing the barrel head ring and the manner of application and fastening.

Fig. 6 is a view in side elevation with parts broken away to show another form of the present invention in which a metal lining for the barrel is provided to hold liquids.

Fig. 7 is an enlarged fragmentary view showing the barrel head construction of the modified form of the invention.

Fig. 8 is a view in vertical section through a modified form of the barrel as used without wooden protecting staves.

Fig. 9 is a view in transverse section showing the joint between the contiguous ends of the barrel as constructed in the manner shown in Fig. 8.

In the drawings, 10 indicates the body of a barrel. This structure may be either designed on the lines of a straight or a bilge barrel and is formed by a plurality of 65 staves 11. The ends of these staves are cut off square and rest against shoulders 12 formed as a part of head rings 13. These rings are adapted to be detachably secured to the opposite ends of the staves. The drum 70 rings are rolled from sheet metal of desired gauge and are formed with a cylindrical portion 14 having a V-shaped circumferential groove or rib 15 therearound. This rib extends into a V-shaped seat 16 formed 75 across each of the staves. The opposite end of the cylindrical portions 14 of the rings are formed with outwardly rolled croze members 17. This portion of the ring is adapted to lie within the line of the outer face of the 80 staves and thus make it possible to readily remove the barrel hoops 18. An annular chine seat 19 is formed by the outer marginal edge of the ring 13 and is adapted to receive a chine ring 20. This chine ring may 85 be of any desired construction and may be of any sectional formation. In Fig. 5 it is shown as being circular, and in Fig. 7 as being rectangular in section. The chine ring is directly disposed around the mouth of 90 the barrel and on top of the barrel heads, thus insuring that any external forces acting along the chine ring and thereagainst would be transmitted to the barrel head and then to the ends of the staves and would be 95 absorbed without damage to the complete structure and particularly to the inner drum in case of use of same.

The staves are held in position around the outer circumferential face of the head 100 ring by means of the hoops 18. These hoops may, under some conditions be con-

tinuous so that they may be driven into place. It may also be convenient to provide them for adjustment as shown in Figs. 3 and 4. Here it will be seen that the contiguous ends of the hoop metal is turned in to receive threaded nuts 21, these nuts in turn receiving the outer threaded ends of an adjusting bolt 22. The bolt with the nuts are disposed within recesses 23 formed in the outer faces of certain of the barrel staves, thus permitting the outer surface of the ring to be comparatively smooth so that the barrel may easily roll. In the case of a bilge barrel all of the rings may be driven into position, although other forms of barrels might require the structure shown in Figs. 3 and 4.

In the form of the invention shown in Figs. 6 to 9 inclusive, the barrel is slightly reconstructed so that an interior container 24 may be enclosed within the wooden barrel structure. This makes it possible to transmit liquids within a container of very light gauge metal, the wooden protecting barrel taking up the shock and which may be removed and replaced, so that repairs can be easily made to the inner drum.

It is also possible to knock down the metal barrel when constructed as shown in Figs. 8 and 9. This is preferably done by forming the head rings as previously described and providing means whereby they may be directly mounted upon the opposite ends of a collapsible metal barrel body 25. This member is formed with a single piece of sheet metal rolled in the shape of a cylinder and being brought together with a joint as shown in Fig. 9. This joint comprises an overlapping V-shaped portion 26 between the sides of which contiguous edge of the barrel sheet metal may be seated. A tight joint is formed by folding the packing strip 27 around this edge and wedging the edge with the strip into the V-shaped flange 26. It is preferable that this packing member shall be of fabric treated with tar, paraffine, or other material impervious to moisture. The end construction of the barrel member 25 comprises an outwardly rolled and circumferentially extending V-shaped groove 28 adapted to be set around the V-shaped ribs 16 of the head rings. The marginal edges of the metal at the ends of the barrel are beaded and are preferably turned over a reinforcing wire. The barrel body is positively held in its assembled position relative to the head rings by means of hoops 29. These hoops are also V-shaped in cross section to provide a seat for the ribs 28. The hoops are held in position by a clamping mechanism similar to that shown in Figs. 3 and 4.

The croze portions 17 at the opposite ends of the barrel are adapted to receive wooden heads 20. These heads are prefer-

ably formed in the sections as shown in Fig. 2 in which duplicate outer segments 31 and 32 are provided and a pair of central removable portions 33 and 34. A joint between the adjacent edges of the sections 31 and 32 and the sections 33 and 34 is formed as shown in the lower portion of Fig. 1 where it will be seen that the edges are tapered so that downward pressure upon the sections 33 and 34 will firmly seal the various sections of the head relative to each other. This sealing operation is brought about by a lever piece 35 which is secured to the outer face of one of the members 33 and overhangs the other member 34. A fastening wire 36 is mounted upon the free end of the lever piece 35 and provides means whereby the wire and a staple 37 may be secured together by a wire or any other suitable lock.

In the operation and use of the barrel structure shown in Fig. 1, the various staves 11 are formed and in this connection it might be stated that by utilizing stock staves, the grooved ends of which may be sawed off, the present structure may be used to produce a barrel of the same size and capacity, as though the staves were used in the construction of the ordinary barrel. The staves after having been formed with the transverse grooves 16 are then ready to be arranged around the cylindrical portions 14 of the head rings. It is to be understood that the head rings are permanently formed in their annular positions and are not supposed to be knocked down. After the staves have been properly placed around the rings, hoop 11 may be driven into position or clamped as previously explained. It will be understood that the chine rings 20 will be permanently placed within the head rings 100 and that the head members 32 to 34 inclusive, may now be disposed in proper position. When the member 35 is fastened down to the member 34, the barrel will be completely sealed and may be very conveniently used in transporting dry, loose material such as cement and the like. In the form of the device shown in Figs. 6 and 7, the same construction is carried out with the additional use of the inner lining 24. With this construction the barrel may be filled with liquids or semi solids and transported from place to place without danger of leakage and at the same time with the assurance that the outer wooden barrel will protect the light metal from the harmful blows and crushing strains which would otherwise be disastrous. In the form of the device indicated in Figs. 8 and 9, the heads as well as the head rings may be disassembled and thereafter 115 the entire barrel body opened up so that a plurality of barrel sheets or staves may be readily nested in a small space.

While I have shown the preferred form of my invention as now known to me, it will be 130

understood that various changes in the construction, combination and arrangement of parts may be made by those skilled in the art without departing from the spirit of the 5 invention as claimed.

Having thus described my invention, what I claim and desire to secure by Letters Patent, is:

1. A barrel comprising a barrel body, a 10 detachable metal head ring so formed as to constitute a croze and a chine, the said croze adapted to contain and seat a head in manner whereby the latter's marginal edge will overlap the rim of the body.

15 2. In a barrel construction, a plurality of staves having transverse V-shaped grooves across their inner faces and adjacent their opposite ends to form a seat for a metal head ring, said ring comprising a croze, a 20 chine and a chine reinforcing ring.

3. A barrel comprising a barrel body formed of a plurality of staves, head rings around which the opposite ends of the staves are secured, a croze portion formed 25 in each head ring, a barrel head adapted to overlap the ends of the staves and seat within the croze.

4. A head structure for knock down barrels comprising a ring portion adapted to 30 extend within the mouth of the body, interlocking means formed beneath the ring and adapted to engage the staves of the barrel, a croze rolled in the ring and extending outwardly over the ends of the barrel staves 35 and a chine ring incorporated within the head ring structure and adapted to circumscribe the mouth of the barrel.

5. A barrel construction comprising metal 40 end rings, each rolled with a croze therearound, and each having a circumferentially extending rib, separable non-metallic heads, one of said heads adapted to be seated within the croze portion of each ring, and an intervening barrel section at the opposite 45 ends of which the heads thus formed are detachably secured to complete a barrel structure.

6. A barrel construction comprising metal

end rings, each rolled with a croze therearound, and each having a circumferentially extending rib, separable non-metallic heads, one of said heads adapted to be seated within the croze portion of each ring, and an intervening barrel section at the opposite ends of which the heads thus formed are detachably secured to complete a barrel structure, and fastening members for securing the intervening structure and the barrel heads in their assembled position. 50

7. In a barrel construction, a solid annular head ring, a circumferentially extending rib rolled around said ring and projecting therefrom and a croze rolled above said rib and carrying a croze ring. 61

8. A barrel comprising a barrel body, a head member, a head ring having a cylindrical portion extending within the mouth of the barrel, a croze formed in the ring in a manner to receive and seat the head in a position whereby the latter's marginal edge will overlap the rim of the barrel body. 7

9. A barrel comprising a barrel body, a head member, a head ring having a cylindrical portion extending within the mouth of the barrel, a croze formed in the ring in a manner to receive and seat the head in a position whereby the latter's marginal edge will overlap the rim of the barrel body, a chine formed at the outer edge of the croze and a reinforcing member secured in the chine. 80

10. A barrel comprising a barrel body, a head member, a head ring having a cylindrical portion extending within the mouth of the barrel, a circumferential groove in 85 the barrel body, a circumferential rib formed of the cylindrical portion of the ring extending in the groove, a croze formed in the ring and adapted to receive and seat the head in a manner whereby the latter's marginal edge will overlap the rim of the body, and a chine ring formed at the outer edge of the croze. 90

In testimony whereof I have hereunto set my hand.

SEWELL A. KNAPP.
